UNITED STATES PATENT OFFICE.

FOSTER MILLIKEN, OF NEW YORK, N. Y.

DESIGN FOR A FRAME FOR DRILLING-MACHINES.

SPECIFICATION forming part of Design No. 26,288, dated November 17, 1896.

Application filed September 28, 1896. Serial No. 607,259. Term of patent 31 years.

To all whom it may concern:

Be it known that I, FOSTER MILLIKEN, a citizen of the United States, residing at New York city, in the county and State of New York, have invented and produced a new and original Design for a Frame for Drilling-Machines, of which the following is a full, clear, and exact description, reference being had to the accompanying drawing, forming a part thereof, which is a perspective view of a frame embodying the features of the design.

The design consists of a base A, which is of substantially rectangular contour, comprising parallel sides 10 and end pieces 11, which are carried beyond the sides and are shown as provided with roller-bearings 12, together with bridge-plates 13 and 13^a, which span the base, extending from side to side. Columns 14 are carried upward from the rear bridge-plate 13, being connected at their upper ends by a cross-head 15, and shorter columns 16 are carried upward from the forward bridge-plate 13^a, while a box-frame B is shown as supported by the forward shorter columns 16 and the rear longer columns 14. This box-

frame contains a bearing-plate 17, which forms a portion of the design of the box-frame, and rods 18 are represented as extending upward from the rear of the base-frame to the cross-head of the rear columns, 30 and similar rods 19 extend from the said cross-head to the front portion of the box-frame B. Horizontal rods 20 extend beyond both sides of the cross-head 15 and connect with a block 20^a. On the rear portion of the horizontal 35 rods 20 a support 21 is apparently adjustably placed, which support maintains a saddle 22 in a position opposite a handle-bar 24, the support 23 for the handle-bar extending through the block 20^a, and this block 20^a is 40 shown as supported by rods 25 resting on the forward portion of the box-frame B.

I claim—

The design for a frame of a drilling-machine herein shown and described.

FOSTER MILLIKEN.
